UNITED STATES PATENT OFFICE.

FRANK BYCROFT KEALL, OF LEICESTER, ENGLAND, ASSIGNOR TO UNITED SHOE MACHINERY CORPORATION, OF PATERSON, NEW JERSEY, A CORPORATION OF NEW JERSEY.

PRESS.

Application filed June 12, 1922. Serial No. 567,690.

To all whom it may concern:

Be it known that I, FRANK BYCROFT KEALL, a subject of the King of England, and residing at Leicester, Leicestershire, England, have invented certain Improvements in Presses, of which the following description, in connection with the accompanying drawings, is a specification, like reference characters on the drawings indicating like parts in the several figures.

This invention relates to presses and more particularly to presses of the type in which power means is provided for moving the presser members relatively to each other in a lateral direction into and out of operative relation to work located between the presser members.

For the purposes of illustration, the invention is embodied in a clicking machine of the type disclosed in Patent No. 921,503, granted May 11, 1909, on application of Arthur Bates. It is to be understood, however, that the invention is not limited to clicking machines but that the invention in its entirety and the several important features thereof may have other and various applications and uses. The commercial form of clicking machine like that illustrated in the patent referred to comprises characteristically a work supporting bed of considerable area and a presser member having a presser surface of an area much less than the work supporting surface. In operating the machine, it is necessary to move the presser member laterally over the work supporting bed into and out of operative relation with respect to work on the bed, and in clicking machines of the type set forth in said patent this is accomplished without undue effort on the part of the operator. In a "heavy-duty" press constructed for operating on relatively large and heavy pieces of work and upon sheet material arranged in a multiplicity of layers, movement of the presser member laterally over the bed is likely to require more effort on the part of the operator than is consistent with an efficient and economical operation of the press and hence it has been proposed to provide power means for moving the presser member laterally over the work supporting bed as well as toward and from the bed in pressure applying operations.

It is an object of this invention to make provision for moving the presser members of a press relatively to each other in a lateral direction through improved power means which will be especially simple in construction and efficient in operation.

In one aspect the invention resides in a press in which a manually operable member is mounted to move with and also relatively to the movable presser member to control the power means for moving the presser member to various selected operative positions upon displacement of the manually operable member within the same limited range relatively to the presser member, the construction and arrangement being such as to bring the presser member to rest in operative position simultaneously with the restoration of the manually operable member to its initial position relative to the presser member.

The invention contemplates also a press in which a presser member is moved laterally of the work supporting bed by power means constructed to be controlled both by a manually operable member under the control of the operator and also by the movable presser member itself so that the manually operable member may move with the presser member without affecting its control of the power means.

In the illustrative construction, the power means for moving the presser member relatively to the work supporting bed comprises fluid-operated means so constructed that power is instantly applied to move the presser member even upon a barely noticeable movement of a manually operable member connected to control the power means. Conveniently the valve mechanism of the fluid-operated means is designed to ensure smooth operation of the presser member with an entire absence of jerking action, in starting and stopping the presser member, and of rebound after the presser member reaches its operative position. In the construction shown this is accomplished by exhaust ports which are slightly open when the supply of fluid is shut off, thus permitting fluid to escape at a time when the momentum of the presser member must be absorbed by counter-pressure in the fluid.

In a preferred embodiment of the inven-

tion, means is provided on the movable presser member for centering or aligning the manually operable power controlling member with respect to the presser member so that upon manipulation of the control member to cause a pressure applying operation the power means for moving the presser member laterally is rendered inoperative.

Other features of construction and novel combinations of parts will be described in the specification and pointed out in the appended claims.

In the drawings:—

Figure 1 is a side elevation, partly in section, of one form of mechanism according to the invention applied to a machine of the type shown in the aforementioned specification;

Fig. 2 is a side elevation of part of the mechanism omitted in Figure 1;

Fig. 3 is a section on the line 3—3 of Figure 2;

Fig. 4 is a plan view, partly in section, of mechanism shown in Figure 1;

Fig. 5 is a front elevation, partly in section of a portion of the mechanism shown in Figure 4;

Fig. 6 is a sectional elevation of a valve with which the mechanism is provided;

Fig. 7 is a section on the line 7—7 of Fig. 6; and

Fig. 8 is a section on the line 8—8 of Fig. 6.

In this particular form of the invention and as applied to a machine of the type aforementioned the handle 10 which controls the tripping of the clutch, by means of which the driving shaft is connected to the driving pulley, is carried on the end of a lever 12 pivoted, so as to be movable vertically and laterally about its pivot 14, which is on the upper side of and about midway of the length of the beam 16. The lever 12 has formed on its upper side a finger 18 which projects over the forward end of a bar 20. Fixed near the forward end of the bar 20 is a cone-ended pin 22 which passes through a slot 24 in the lever 12 extending lengthwise of the lever and of a width sufficient to allow of the passage of the pin 22. Below the pin 22 the beam 16 has formed on it a boss 26 having upwardly inclined walls 28 leading to an opening at the bottom, which opening or passage 30 is slightly larger than the diameter of the pin 22. When the hand-lever 12 is depressed to trip the clutch of the machine the lower end of the pin 22 engages one of the inclined walls 28, if the hand lever 12 is at this time displaced laterally of the center of the beam, and the hand-lever is thereby centralized during its further downward movement. The bar 20 at its rear end is bent vertically and is fixed in a boss 32 extending forwardly from a ring 34 rotatably mounted on the

forwardly extending arm 36 of a lever 38 pivoted to the frame of the machine on a shaft 40. The arm 36 is itself ring shaped and surrounds the column 42, the internal diameter of the ring being somewhat larger than the column to allow the arm to swing about the shaft 40. The arm 36 has an upwardly extending flange about which the ring 34 turns and the ring is held against vertical movement by a ring-shaped plate 44 fastened on to the flange. A stop 46 on the plate 44 limits the upward movement of the arm 36 under the influence of a spring (not shown) attached to the arm and to the frame, by its engagement with a portion of the frame. The ring 34 is formed on its outer circumference with bevel teeth 48 which mesh with a bevel-pinion 50 fixed on the upper end of a shaft 52 having a bearing in the arm 36. A collar 54 pinned on the shaft 52 below the lower face of the bearing prevents upward movement of the shaft. The rear arm 56 of the lever 38 is connected to the upper end of a vertical rod 58, the lower end of which is connected to the usual clutch mechanism.

The lower end of the shaft 52 is connected by a universal coupling 60 to the upper end of a shaft 62 rotatably mounted in a bearing formed on a bracket 64 fixed in the frame of the machine. The shaft 62 has, pinned on it near its upper end a collar 66 which bears against the upper face of the bearing, and at its lower end has pinned on it a bevel-pinion 68. The pinion 68 meshes with a bevel-pinion 70 rotatably mounted on a horizontal shaft 72. The shaft 72 is rotatably mounted in bearings formed on the bracket 64 and has fixed on it a bevel-pinion 74. The bevel-pinions 70 and 74 both mesh with a bevel-gear 76 fixed on the upper end of a shaft 78 rotatably mounted in a swinging frame 80 hung on the shaft 72. The swinging frame 80 has pivotally connected to it near its lower end on a stud 82 one end of a valve-controlling rod 84. The rod extends horizontally towards the right of the machine and at its outer end is cam-shaped or tapered as at 85.

The end 85 of the rod 84 passes through the lower slotted end of a tube 86 (Fig. 6) and is supported by a pin 88 fixed in the tube. The tube is fixed by screws 90 to a cap 92 which is fastened to the lower end of a valve casing 94. The valve casing 94 is secured in a boss 96 formed on a bracket 98 (Figs. 1 and 4) fastened by bolts 100 (Fig. 1) to the frame of the machine. Secured to the upper end of the valve casing 94 by screws 102 (Fig. 6) is a cap 104 recessed at 106 to receive the upper end of a spring 108 which at its lower end enters a recess 110 formed in the upper end of a plunger 112, slidingly mounted in a central bore of the valve casing 94, and to urge the plunger 112

downwardly. The plunger 112 has secured to its lower end a sleeve 114. The sleeve at its upper end has on it a flange 116 which is slotted to receive a screw 118 by which the sleeve is attached to the plunger. The sleeve 114 just below the flange 116 is cut away at 119 so that the bore 120 of the sleeve connects with a recess 122 formed in the cap 92. Slidingly mounted in the tube 86 is a plunger 124 which rests on the valve-controlling rod 84. The plunger 124 is tapered at its upper end and enters the lower end of the bore 120 of the sleeve 114. Oil under pressure is admitted from a suitable supply 10 through a pipe 128 into the recess 122 and passes down the bore 120 of the sleeve 114 and through the space between the lower end of the bore and the tapered end of the plunger 124. The oil is then returned to its 20 source of supply by any suitable means. The space between the lower end of the bore 120 and the tapered end of the plunger 124 is normally such that the pressure of the oil in the recess 122 balances the pressure of 25 the spring 108 and the plunger 112 is maintained in a neutral position (i. e. that shown in Figure 6 of the drawings). If the valve-controlling rod 84 is moved to the right in Figure 6 the plunger 124 will, by reason of 30 the tapered end of the rod 84, be raised and the space between the tapered end of the plunger 124 and lower end of the bore 120 will be more nearly closed so that the pressure of the oil in the recess 122 will be increased and the plunger 112 thereby raised 35 against the action of the spring 108. If the rod 84 is moved to the left in Figure 6 the plunger 124 will be lowered and the space between the tapered end of the plunger and lower end of the bore 120 will be increased 40 and the pressure of the oil in the recess 122 lowered and the plunger 112 will be moved downwardly by the spring 108. The plunger 112 has formed on it enlarged portions 140 45 which control the flow of fluid, under pressure, through various ports and passages formed in the boss 96 and valve casing 94. These ports comprise an inlet port 144, at the end of inlet pipe 146, connected to a 50 suitable pump or other source of supply, an exhaust port 148 through which the fluid returns to the supply, and ports 150, 154 connected to cylinders 158, 160 (Fig. 4) fixed on opposite ends of the bracket 98 55 which is provided with bearings 164, 166 in which is slidingly mounted a piston 170. When the plunger 112 is raised, as hereinbefore described, the fluid will flow from the inlet port 144 up the central bore of the 60 valve casing 94, through passages 174, 174 to a cavity 176 and through the port 154 and a tube 180 (Fig. 4) to the cylinder 160, and the piston 170 will be moved lengthwise in one direction. During such movement, fluid in the other cylinder 158 will

be exhausted along the pipe 190 (Figs. 4 and 6) through the port 150 along cavity 192 and passages 194, 194 down the central bore of the valve casing 94, and through an opening 198 to the port 148 and exhaust 70 pipe 200 by way of cavity 202. Conversely if the piston 170 is lowered the fluid will flow in the opposite direction and the piston 170 will be moved in the opposite direction. When the plunger 112 is lowered, the fluid 75 will flow from the inlet port 144 down the central bore of the valve casing 94, through passages 194 and through port 150 to cylinder 158 by way of the tube 190. Drainage tubes 210 are provided to take the oil from 80 a collecting cavity 212 in each of the bearings 164, 166.

The piston 170 has formed on its front face a rack 220 which meshes with a gear segment 224 fastened to the beam 16. The segment 224 is concentric with the beam supporting column 42 and is fixed at the rear of the semi-circular portion of the beam. The segment is of such a length, (Fig. 1) 85 heightwise of the beam, as to allow of vertical cutting movement of the beam without its becoming disengaged from the rack. The piston 170 has formed on its upper face a second rack 230 which meshes with a gear 234 (Fig. 1) fixed on the forward end of 90 the shaft 72. 95

When it is desired to move the beam laterally in one direction or the other, the handle 10 is moved in that direction and through the toothed ring 34 and bevel-pinions 50, 68, the bevel-pinion 70 which is rotatably mounted on its shaft 72 is rotated and rotates the bevel gear 76 carried on the swinging frame 80. At this time the bevel-pinion 74 which is fixed on its shaft 72 is prevented from rotation by the engagement of the gear 234 on the forward end of the shaft 72 with the rack 230 on the upper face of the piston 170 so that the bevel gear 76 during its rotation travels round the, at 100 this time fixed, bevel pinion 74 and swings the swinging frame 80 about its pivot shaft 72. The movement of the swinging frame 80 moves the valve-controlling rod 84 lengthwise to admit fluid to one or other of 110 the cylinders 158, 160. The piston 170 is thereby moved endwise and through the rack 220 and gear segment 224 swings the beam 16 laterally. 115

During the simultaneous movement of the beam 16 and handle 10 the bevel-pinions 70 and 74 are rotated at the same speed in opposite directions, the pinion 70 by the movement of the handle 10 through the toothed ring 34 and the pinion 74 by the rack 230 125 on the upper face of the piston 170 so that the gear-wheel 76 with which they both mesh is idly rotated and no movement is imparted to the swinging frame 80.

The movement of the beam 16 continues 130

so long as the displaced relationship of the handle 10 and beam 16 is maintained and when the handle 10 arrives at the desired position the operator merely ceases 5 to impel it. Stopping of the handle 10 also stops the rotation of the bevel-pinion 70 and during continued movement of the beam 16 the bevel-pinion 74 continues to rotate, through the rack 230 on the upper face of the piston 170, and rotates the bevel-gear 76 which rolls round the now stationary bevel-pinion 70 and swings the swinging frame 80 in the opposite direction to that in which it was swung to open the 10 valve at the upper end of plunger 124, and thereby moves the valve toward closing position and stops the movement of the beam. The handle 10 is then depressed to trip the clutch and effect the 15 cutting stroke of the beam. A reverse movement of the handle 10 causes the beam to be removed from over the knife to any desired position determined by the stopping 20 of the handle. The control of the valve operating rod 84 is exercised both by the operator, through the handle 10 and connections including the pinions 68, 70, and by the beam, through the pinions 234, 74, the 25 construction embodying a differential mechanism in the operation of which the moving beam tends always to move the valve operating rod 84 in the opposite direction to that in which it is initially moved by the operator. As soon as the operator stops 30 moving the handle the beam exercises control of the valve operating rod 84 and brings the latter to neutral position the instant the handle lever 12 and beam are in exact longitudinal alinement. So long as the handle lever is displaced laterally of the beam the latter will continue to move. It will be observed that movement of the handle lever 35 relatively to the beam is always within the same limited range irrespective of the distance traveled by the beam in reaching the selected operative position.

The plunger 112 is so arranged that when the handle is moved to the right or left, as the case may be, the inlet port 144 is opened 40 to admit fluid to the appropriate cylinder 158 or 160, the exhaust opening 197 or 198 (Fig. 6) for that cylinder is closed and the exhaust opening 198 or 197 for the other cylinder is opened. When the handle is in 45 its central position on the beam both the exhaust openings are partly open, the enlarged portions 140 of the plunger 112 being reduced in diameter as at 240 for the purpose so as to prevent sudden stoppage of the beam and vibration caused thereby, and to prevent a vacuum being formed behind the moving piston and consequently return 50 movement of the piston caused thereby which might re-open the valve.

By appropriate proportioning in this way

of the amount of closing of exhaust ports as the beam catches up with the handle when the latter is stopped, a smooth stoppage of the beam without jerky action can be secured, and owing to the use of the relay 55 valve formed by the parts 120, 124, so sensitive a control can be obtained that a barely noticeable displacement of the handle on the beam sets the latter in full motion. Owing to the friction in the extended connecting parts between the pinion 70 and the handle 10, the cessation of impulse on the handle immediately stops the beam without there being any need for a definite reverse pull or resistance on this handle. In 60 the result the operator is entirely under the illusion that the beam has moved solely by reason of his own effort, although apparently without inertia or momentum, and the advantages of speed of operation and absence of fatigue which result from such an arrangement and construction of parts are 65 manifest.

In operating with the machine, sheet material is placed upon a work supporting bed or block (not shown) and a die positioned on the material in accordance with the operator's plan for securing economical cutting of the material. Then the presser member or beam 16 is moved, by proper manipulation of the handle 10, until it arrives over the die whereupon depression of the handle 10 serves to terminate the lateral movement of the presser member and to 70 initiate a pressure applying operation by which the die is forced through the material on the bed. Slight pressure on the handle 10 in the desired direction will cause movement of the presser member in that direction to uncover the die. These operations 75 are repeated until the material on the bed is converted into blanks of the number and size desired.

Having described my invention, What I claim as new and desire to secure by Letters Patent of the United States is:—

1. In a machine of the character described, a work supporting bed, a presser member movable toward and from the bed in pressure applying operations and also laterally of the bed into and out of operative relation to work located on the bed, power means for moving the presser member laterally over the bed, a manually operable member movable with the presser member and also relatively thereto for controlling said power means, and connections between the power means and the manually operable member for causing the power means to bring the presser member to rest simultaneously with the relative movement of the manually operable member and the presser member into alinement.

2. In a machine of the character described, a work supporting bed, a presser member

- movable toward and from the bed in pressure applying operations and also laterally of the bed into and out of operative relation to work located on the bed, power means for 5 moving the presser member laterally over the bed, a manually operable member movable with the presser member for controlling the power means and also movable always to the same predetermined extent relatively to the presser member in effecting operation of the power means to cause movement of the presser member to various selected positions over the work supporting bed, and connections between the presser 10 member and the power means for maintaining the latter in operation so that the manually operable member may move with the presser member without affecting its control of the power means.
- 20 3. In a machine of the character described, a work supporting bed, a presser member movable toward and from the bed in pressure applying operations and also laterally of the bed into and out of operative relation 25 to work located on the bed, power means for moving the presser member laterally over the bed, a manually operable member movable with the presser member and also relatively thereto for controlling 30 said power means, and connections between the manually operable member and the power means controlled by the presser member so that the manually operable member may be unaffected by its movement along with 35 presser member and may be operative only upon movement relative to the presser member.
- 40 4. In a machine of the character described, presser members relatively movable toward and from each other in pressure applying operations, power means for moving the members relatively to each other in a lateral direction, said power means comprising a differential mechanism, and a manually operable member movable with the movable 45 presser member for controlling the power means through said mechanism whereby relative movement of the presser members in a lateral direction may be accurately controlled by the operator.
- 50 5. In a machine of the class described, a work supporting bed, a presser member movable toward and from the bed in pressure applying operations, power means for moving the presser member laterally of the bed, and a manually operable member movable with the presser member for controlling the power means, said power means including differential mechanism, and connections 55 between said mechanism and the manually operable member and the presser member by which movement of the presser member may be accurately controlled.
- 60 6. In a machine of the character described, a work supporting bed, a presser member movable toward and from the bed in pressure applying operations and also laterally of the bed into and out of operative relation to work located on the bed, power means for 65 moving the presser member laterally over the bed, a manually operable member movable with the presser member for controlling said power means, said manually operable member being also movable relatively to the presser member and so connected to the power means that the distance the presser member moves is directly proportional to the length 70 of time the manually operable member is held in operative position, and connections between the presser member and the power means for controlling the latter so that the power is shut off when the presser member 75 comes into predetermined relation with respect to the manually operable member.
- 80 7. In a machine of the character described, a work supporting bed, a presser member movable toward and from the bed in pressure applying operations; power means for moving the presser member laterally of the bed, and a manually operable member for controlling said power means, said means comprising fluid-operated mechanism 85 provided with an inlet valve and exhaust ports which remain slightly open when the inlet valve is closed, so as to cushion the movement of the beam and prevent rebound of the beam during the operation of the machine.
- 90 8. In a machine of the character described, a work supporting bed, a presser member movable toward and from the bed in pressure applying operations, power means for moving the presser member laterally of the bed, said means comprising a plunger geared to the presser member and reciprocable in opposite directions to move the beam over the bed, means for causing fluid to operate 95 selectively on the plunger to move the same, connections between the plunger and the rest of the power means for controlling the latter, and a manually operable member for initiating lateral movement of the presser member.
- 100 9. In a machine of the character described, a work supporting bed, a presser member movable toward and from the bed in pressure applying operations and also laterally of the bed into and out of operative position with respect to work located on the bed, power means for moving the presser member laterally over the bed comprising a fluid-operated mechanism, and a valve in said mechanism automatically operative to relieve the pressure as the presser member comes to rest so that the fluid operates as a cushion to ensure against jerking action 105 and prevent rebound of the presser member.
- 110 10. In a machine of the character described, a work supporting bed, presser members relatively movable toward and from each other in pressure applying operations and also relatively to each other in a lateral 115
- 120
- 125
- 130

- direction into and out of operative position with respect to work located between the presser members, and power means for moving the presser members relatively to each other in a lateral direction comprising a hydraulic mechanism having a valve automatically operative to relieve the pressure at the starting and stopping of the lateral movement so as to ensure smoothness in movement and the absence of jerkiness and rebound both in starting from a position of rest and stopping at the desired operative position.
11. In a machine of the character described, a work supporting bed, a presser member movable toward and from the bed in pressure applying operations and also laterally of the bed into and out of operative position with respect to work located on the bed, power means for moving the presser member laterally of the work supporting bed comprising fluid-operated mechanism, a member for controlling said mechanism movable in one direction through force exerted by the operator and movable in a reverse direction through connections with the movable presser member, and a manually operable member under the control of the operator for moving said controlling member whereby differential movement of the manually operable member and the presser member controls the power means to effect accurate positioning of the presser member.
12. In a machine of the character described, a work supporting bed, a presser member movable toward and from the bed in pressure applying operations and also laterally over the bed into and out of operative position with respect to work located on the bed, power means for moving the presser member laterally of the bed comprising a plunger geared directly to the presser member and arranged to be moved in opposite directions by fluid under pressure, and valve mechanism automatically operative to relieve the pressure as the presser member comes to rest so that the fluid operates as a cushion to ensure against jerking action and prevent rebound of the presser member.
13. In a machine of the character described, a work supporting bed, a presser member movable toward and from the bed in pressure applying operations and also laterally over the bed into and out of operative position with respect to work located on the bed, and power means for moving the presser member laterally over the work supporting bed comprising an hydraulic mechanism having valves automatically operative to relieve the pressure at the starting and stopping of the presser member so as to ensure smoothness in movement and the absence of jerkiness and rebound of the presser member both in starting from a po-

sition of rest and stopping at the desired operative position.

14. In a machine of the character described, presser members relatively movable toward and from each other in pressure applying operations and also in a lateral direction relatively to each other into and out of operative relation with respect to work located between the presser members, power means for moving one presser member laterally of the other comprising fluid-operated mechanism, a member for controlling said mechanism movably in one direction through force exerted by the operator and movable in a reverse direction through connections with the movable presser member, and a manually operable member under the control of the operator for moving said controlling member whereby differential movement of the manually operable member and the presser member controls the power means to effect accurate positioning of the presser member.

15. In a machine of the character described, a work supporting bed, a presser member movable toward and from the bed in pressure applying operations and also laterally over the bed into and out of operative relation to work located on the bed, power means for moving the presser member laterally over the bed, a manually operable member movable relatively to the presser member for controlling said power means, and means for returning the manually operable member into exact alignment with the presser member to effect disconnection of said power means with respect to the presser member.

16. In a machine of the character described, a work supporting bed, a presser member movable toward and from the bed in pressure applying operations and also laterally over the bed and out of operative relation to work located on the bed, power means for moving the presser member laterally over the bed and for causing pressure applying operations of the presser member, a manually operable member movable relatively to the presser member for controlling the power means, and means for centering said manually operable member with respect to the presser member upon manipulation of the former to initiate a pressure applying operation whereby the lateral movement of the presser member is discontinued.

17. In a machine of the character described, a work supporting bed, a presser member movable toward and from the bed in pressure applying operations and also laterally of the bed into and out of operative relation to work located on the bed, power means for moving the presser member laterally over the bed and for causing pressure applying operations of the presser

member, a manually operable member movable relatively to the presser member for controlling said power means, and co-operating members located respectively on the 5 manually operable member and on the presser member for centering the controlling member relatively to the presser member whereby lateral movement of the presser member ceases upon initiation of a pressure 10 applying movement of the presser member.

18. In a machine of the character described, a work supporting bed, a presser member movable toward and from the bed in pressure applying operations and also 15 laterally over the bed into and out of operative relation to work located on the bed, a post for supporting the movable presser member for swinging movement over the bed, power means for causing movement of 20 the presser member laterally over the bed, means operating to cushion the movement of the beam and prevent rebound thereof at the termination of a lateral movement of the beam, and a manually operable member for 25 controlling said power means.

19. In a machine of the character described, a work supporting bed, a presser member movable toward and from the bed in pressure applying operations and also 30 laterally of the bed into and out of operative relation to work located on the bed, power means for moving the presser member laterally over the bed, a post for supporting the presser member for swinging movement 35 laterally over the work supporting bed, power means comprising an endwise movable plunger directly connected to the presser member for moving the latter laterally over the bed, and a manually operable member 40 movable with the presser member for controlling said power means.

20. In a machine of the character described, a work supporting bed, a presser member movable toward and from the bed in 45 pressure applying operations and also laterally of the bed into and out of operative relation to work located on the bed, power means for moving the presser member laterally over the work supporting bed, a 50 manually operable member movable with the presser member for controlling the power means, connections between the manually operable member and the power means com-

prising a pivoted member, and connections from the presser member to the pivoted member whereby the presser member also controls said power means. 55

21. In a machine of the character described, a work supporting bed, a presser member movable toward and from the bed in pressure applying operations and also laterally over the bed into and out of operative relation to work located on the bed, hydraulic means for moving the presser member laterally over the bed, a post for supporting the presser member for swinging movement laterally over the work supporting bed, and a manually operable member movable with the presser member for controlling said hydraulic means. 60 65

22. In a machine of the character described, a work supporting bed, a presser member movable toward and from the bed in pressure applying operations and also laterally of the bed into and out of operative relation to work located on the bed, power means for moving the presser member laterally over the work supporting bed comprising fluid-operated mechanism having a control valve, a manually operable member movable with the presser member for controlling the power means, connections between the manually operable member and the power means comprising a member for controlling said valve, and connections from the presser member to the valve controlling member whereby the presser member also controls said power means. 70 75 80 85

23. In a machine of the class described, a work supporting bed, a presser member movable toward and from the bed in pressure applying operations, power means for moving the presser member laterally of the bed, and a controller movable with and also relatively to the presser member for controlling the power means to move the presser member to various positions upon displacement of the controller within the same limited range relatively to the presser member and to bring the presser member to rest simultaneously with the restoration of the controller to its initial position relative to the presser member. 90 95 100

In testimony whereof I have signed my name to this specification.

FRANK BYCROFT KEALL.
